Attorney

UNITED STATES PATENT OFFICE.

ALFRED C. STEWART, OF PASADENA, CALIFORNIA.

ELECTRICALLY-OPERATED PUMP.

Application filed August 6, 1923. Serial No. 656,137.

This invention relates to a pump adapted for operation by alternating electric current and the main object of the invention is to provide a pump of this character with means whereby the alternating current is so controlled as to ensure more effective operation of the pump and to avoid certain difficulties arising from the rapid alternation of the electrical current in the operating means for the pump.

A further object of the invention is to provide in a pump of this character improved means for elastically supporting the operating member of the pump to synchronize or time the same with the alternating current.

The accompanying drawing illustrates an embodiment of my invention and referring thereto:

20 Fig. 1 is a partly sectional side elevation of a pump showing automatic circuit controlling means in connection therewith for controlling the alternating current as hereinafter described.

25 Fig. 2 is a section on line 2—2 in Fig. 1. The pump shown in the drawing may comprise a casing formed with a cylinder 1 in which is adapted to operate a piston 2, suitable inlet and outlet valves being provided 30 for control of the admission and exhaust of the fluid, gas, or vapor, which is to be pumped or compressed. Said outlet valve may consist of a valve disk 3 mounted at the top of cylinder 2 and adapted to close 35 by gravity and control the flow of the compressed medium to an outlet connection 4. The piston 2 may be adapted to move below the bottom of cylinder 1 in its down stroke so as to open communication to inlet 7 40 through which the fluid, gas, or vapor to be pumped is supplied to the interior of the casing.

The casing of the apparatus further comprises a downward extension 8 from the cylinder portion 1, said extension being connected at its lower end to a casing member 10, forming a field member for an electro-magnetic solenoid coil or winding 11 which is surrounded or enclosed by said casing 10, and is adapted to cooperate with a core member 12 of magnetic material which is adapted to reciprocate within said solenoid coil or winding. The top of the casing 10 may have a downward extension 13 of magnetic material projecting within the solenoid coil or winding 11 to reduce the reluctance of the

magnetic circuit. Solenoid core 12 is of suitable magnetic material, for example, soft iron, preferably laminated or cut to minimize eddy loss and is attached to rod 14 60 which is connected to the piston 2 aforesaid, so as to cause operation of said piston by the reciprocation of said rod. Casing 10 may be provided with a downward extension 15 for receiving the core 12 when in lowermost position. The cylinder 1 may be closed at its upper end by a cap member 16 and the several casing parts 1, 16, 8, 10, and 15, are tightly connected or joined in such a manner as to provide a gas tight enclosure for 70 the operating parts, including the piston 2 and the operating core 12.

Means are provided for elastically or resiliently mounting reciprocating member or unit comprising piston 2 and core 12, said means preferably comprising a flexible tie-member 17 consisting for example of a wire, band, cable, or chain which passes through a transverse opening 18 in the rod 14 aforesaid so as to be connected to and to extend 80 transversely of the reciprocating unit, and is connected at either end to a spring supported member 19 adapted to slide in a tubular radial extension 20 from the casing body 8, a spring 21 being interposed between said 85 member 19 and a shoulder 22 at the inner end of said tubular radial extension in such a manner that the flexible member 17 is held taut by the operation of said spring means 21. The connection of tie-means 17 to spring 90 supported member 19 is by means of a screw 24 which screws in member 19 so as to adjust the tension of tie-means 17. The radial tubular extension 20 is closed by cap or plug 23 at its outer end forming a gas-tight enclosure therefor.

The solenoid coil or winding 11 is connected to a source of alternating electric current preferably through a circuit interrupter which is adapted to interrupt the alternating current in such a manner as to permit current impulses to pass to the operating solenoid coil or winding in one direction only and to cut off current impulses or wave portions in the opposite direction. 100 For this purpose any suitable circuit interrupter operated in synchronism with the alternating current may be used for example, as shown in Fig. 1, I may provide a polarized electro-magnetic circuit controller comprising a permanent magnet 28, and an armature 29 having its winding connected in 105 110

a shunt circuit indicated at 30 and 31 to the wires 33 and 32 of an alternating current supply circuit. A circuit controlling arm 34 may be connected to the armature 29 and 5 is connected by wire 35 with the wire 32 of the said supply circuit and a fixed contact 36 may be provided, adapted to cooperate with the said circuit controlling arm 34 to close the circuit during those half- 10 waves of the alternating current which it is desired to transmit to the operating solenoid, said contact 36 being connected to a wire 37 leading to solenoid coil 11 and the other wire 33 of the supply circuit being 15 connected to the other end of solenoid 11. The above described intermittent operation 20 of the circuit controlling arm 34 is caused by the fact that armature 29 together with said circuit controlling arm is caused to swing to the left in Fig. 1 so as to make contact with contact 36 upon passage of the current impulses in one direction and to swing to the right so as to break such contact upon passage of the current impulses 25 in the other direction. Current controlling arm is sufficiently elastic to provide for maintenance of contact during substantially a half wave period. Connection is therefore 30 made between circuit controller 34 and contact 36 during alternate half waves of the current so that the current impulses supplied to the solenoid are always in the same direction and are of a definite frequency corresponding to the frequency of the alternating current. The electric circuit connections 35 enter the casing 10 through gas-tight bushings 38.

The operation is as follows:

Alternating current of suitable potential 40 difference supplied to the wires 32 and 33 is controlled by the operation of the electro-magnetic circuit closer above described so that alternate wave portions corresponding 45 to the current impulses in the same direction, and representing an intermittent unidirectional current, passes through the wires 25 and 26 to the solenoid 11 so that said winding is alternately energized and de-energized. During the periods of energization of said winding the solenoid core 50 12 is drawn upwardly within the winding and the resulting upward movement of the piston 2 causes compression of the gas or vapor within the piston cylinder 1. During 55 the ensuing half-wave period while the solenoid coil 11 is deenergized core 12 is returned to normal position by operation of gravity and of the spring means aforesaid. By the operation of the core as above 60 described the fluid is pumped from the inlet 7 to the outlet 4. In order to ensure a full stroke of the reciprocating unit and to provide for maximum efficiency of operation the resilient support for the reciprocating 65 unit is tensioned by adjustment of each ad-

justing device 24 so as to proportion the restoring force due to the tension of the springs 21 to the mass of the reciprocating unit that the natural period of oscillation of the said reciprocating unit corresponds 70 to the period of alternation of the energizing current, or more properly the period between successive wave impulses of the intermittent current produced by operation of the circuit closer on the alternating current 75 supplied thereto.

It should be noted that, as shown in Fig. 1, the position of the resiliently supported flexible member 17 with respect to the motion of the piston 2 is such as to tend to 80 hold said piston in a position at an intermediate point of its stroke and to resiliently resist the movement of the piston in either direction from such position. While the piston is alternately drawn upward and 85 downward by the solenoid coil and the force of gravity respectively, the tension means 17 resiliently resists its motion in each direction. By reason of this fact such tension means are particularly effective in tending 90 to give the reciprocating member a natural period of oscillation, and by suitable adjustment of screws 24 the resisting force of the springs 21 may be made such as to make 95 this natural period equal to the period between successive current impulses.

The several casing members 1, 16, 8, 23, 10, and 15 are preferably all in tight connection and closed so as to form a gas-tight enclosure for the pump and the operating means therefor. As so constructed the device is applicable with especial advantage in the compression of condensable vapors as a part of a refrigerating system. In using the above described pump in a 105 refrigerating apparatus the inlet and the outlet valves of the pump are connected in the refrigerating line in the usual manner of refrigerating plants using a volatile liquid or readily condensable vapor, such as rhigolene, sulfur dioxide, etc., the function 110 of the pump being to compress the expanded vapor so that on subsequent cooling it will condense to liquid form and can be re-expanded to perform the refrigerating operation. Inasmuch as there are no stuffing boxes or outside connections for operating the pump, all of the working parts being 115 contained within the gas tight or hermetically sealed casing there is no leakage of the refrigerating medium from the pump into the outer air. This is an important advantage especially in the smaller refrigerating units as such units have to be operated with a minimum of care and attention 120 and it is highly desirable that the supply of refrigerating medium furnished with such installation should last indefinitely or at least for as long a time as possible.

Various modifications may be made in 130

the apparatus as described without departing from my invention, for example, the core member which operates the piston may be so arranged relative to its operating 5 solenoid as to be drawn downwardly by the action of the solenoid and raised by the action of the spring. This change in operation of the device may be brought about by inverting the device shown in the drawing or 10 by suitably modifying the position of the core with relation to the solenoid coil. Furthermore the device described may be used in any angular position either horizontal or vertical.

15 What I claim is:

1. An electrically operated pump comprising a cylinder, a piston working therein, a core in connection with said piston and forming therewith a reciprocating unit, resilient means connected to said reciprocating unit and tending to hold the same in an intermediate position and to resiliently resist its movement in either direction from such position, a solenoid coil in position to 25 cause, upon energization, movement of said reciprocating unit in one direction from such intermediate position, means for moving said reciprocating unit in the other direction from such intermediate position upon 30 de-energization of said coil, means for supplying intermittent unidirectional cur-

rent impulses of definite frequency to said solenoid coil to energize the same, and means for adjusting said resilient means so as to cause the reciprocating unit in its resulting alternate motion in opposite directions from said intermediate position to have a natural frequency of oscillation equal to the frequency of such current impulses. 35

2. An electrically operated pump comprising a casing provided with a cylinder, a piston working in said casing, a core of magnetic material in connection with said piston and forming therewith a reciprocating unit, a solenoid adapted to operate said core, 40 means for supplying intermittent unidirectional current impulses to said solenoid, whereby said reciprocating unit is caused to reciprocate, and spring supporting means in connection with said core comprising a 45 flexible member connected to and extending transversely of said reciprocating unit and spring means for tensioning said flexible member. 50

3. A construction as set forth in claim 2 and comprising in addition means for adjusting the spring tension on said flexible means. 55

In testimony whereof I have hereunto subscribed my name this 24th day of July, 1923.

ALFRED C. STEWART.
